A. W. HARRISON & H. W. BASCOM,
SANITARY DUST MOP SHAKER,
APPLICATION FILED JUNE 27, 1917.

1,245,226.

Patented Nov. 6, 1917.

UNITED STATES PATENT OFFICE.

ALICE W. HARRISON AND HELEN WARD BASCOM, OF PASADENA, CALIFORNIA.

SANITARY DUST-MOP SHAKER.

1,245,226.

Specification of Letters Patent.

Patented Nov. 6, 1917.

Application filed June 27, 1917. Serial No. 177,394.

To all whom it may concern:

Be it known that we, ALICE WARD HARRISON and HELEN WARD BASCOM, citizens of the United States, residing at Pasadena, in the county of Los Angeles and State of California, have invented new and useful Improvements in Sanitary Dust-Mop Shakers, of which the following is a specification.

This invention relates to a sanitary dust mop cleaner.

It is the principal object of this invention to provide a simple device within which a dust mop may be cleaned and by which the mop may be conveniently shaken without danger of scattering the dust liberated from the mop.

Another object of this invention is to provide a container within which the dust from the mop will be collected and from which it may be easily cleaned.

Other objects will appear hereinafter.

The invention is illustrated, by way of example, in the accompanying drawings in which:

25 Figure 1 is a view in perspective illustrating the cleaning device.

Fig. 2 is a view in vertical section, as seen on the line 2—2 of Fig. 1, and particularly illustrates the details of the device, as well as the manner in which a mop is accommodated therein.

Fig. 3 is an enlarged fragmentary view of the fastening means used for holding the lid of the canister in place.

35 Referring more particularly to the drawings, 10 indicates a large cylindrical canister forming the body portion of the device. This canister is provided with an open mouth adapted to be closed by a telescoping cover 11 having a circular flange at its top which seals the mouth. Bayonet slots 12 are formed at opposite sides of the cover and are adapted to receive fixed lock pins 13 which extend inwardly and from diametrically opposite sides of the can. The can and its cover are preferably formed of metal of a suitable gage and the can top is therefore reinforced by a wooden reinforcing disk 14, upon which is secured a dash-pot

end to the reinforcing disk 14 and by its upper end to a plunger disk 17. A central 55 opening 18 is formed through the plunger disk 17 and is in vertical alignment with a similar opening 19 formed through the cover of the canister and its reinforcing disk. These openings are provided to receive the 60 handle 20 of a dust mop 21. A hole 22 is formed through the handle of the mop at a desired point along its length and is adapted to receive a removable pin 23, for a purpose which will be hereinafter set forth. The 65 pin is fastened to the plunger disk 17 by a chain which prevents it from being lost.

When a mop is to be cleaned, a paper lining 24 is positioned within the canister and thereafter the handle of the mop is passed 70 upwardly through the opening 19 in the cover and the opening 18 in the plunger disk, after which it is secured by means of the pin 23. It will be observed that when the mop is in this position it will be circumscribed by the helical spring 16 and will be resiliently supported as it rests upon the plunger disk 17 by means of the pin 23. The cover may then be placed over the canister and locked in position by the lock pins 80 13 which will register with the bayonet slots 12. The mop handle may then be grasped and reciprocated against the expansive action of the spring 16. This churning movement will cause the mop 21 to be violently 85 raised and lowered and will act to throw the strands of the mop outwardly to liberate the dust and lint collected thereby. It will be evident that continuous movement of the mop for a short period of time will act to 90 clean the mop and make it ready for further use. After this has been done, the cover may be removed, the pin 23 withdrawn from the handle, and the mop taken out for use. The canister may then be cleaned by removing the paper lining 24, which is in the form of a bag, and will thus insure that the interior of the canister will not become dirty.

It will thus be seen that the mop cleaner here disclosed provides simple means for receiving and inclosing a dust mop and easily operated means for effectively liberating dust and lint therefrom and catching it in a sanitary manner.

While we have shown the preferred construction of our sanitary dust mop shaker

as now known to us, it will be understood that various changes in the combination, construction and arrangement of parts may be made by those skilled in the art without departing from the spirit of our invention.

We claim:

10. 1. A sanitary dust mop cleaner comprising a dust receptacle, a cover for the dust receptacle adapted to be removably fastened in place and having a mop handle opening, and means upon the cover for resiliently and detachably holding the mop handle.
15. 2. A sanitary dust mop cleaner, comprising a canister having an open top, a removable cover adapted to close said top, means for detachably locking the cover upon the canister, a dash-pot secured upon the cover and disposed in vertical alinement with the center of the canister, a plunger disk mounted within said dash-pot, a cushion spring resiliently supporting said disk, and means whereby the handle of a mop may be supported by said disk and reciprocated against the expansion of the spring in a manner to cause the mop to be violently shaken within the canister, and dust removed therefrom, and a removable lining adapted to be positioned within the canister to receive the dust and lint from the mop.
20. 3. A sanitary dust mop cleaner, comprising a canister having an open top, a removable cover adapted to close said top, means for detachably locking the cover upon the canister, a dash-pot secured upon the cover and disposed in vertical alinement with the center of the canister, a plunger disk mounted within said dash-pot, a cushion spring resiliently supporting said disk, and means whereby the handle of a mop may be supported by said disk and reciprocated against the expansion of the spring in a manner to cause the mop to be violently shaken within the canister and dust removed therefrom.

cause the mop to be violently shaken within 25 the canister and dust removed therefrom.

3. A sanitary dust mop cleaner, comprising a canister having an open top, a removable cover adapted to close said top, means for detachably locking the cover upon the 30 canister, a dash-pot secured upon the cover and disposed in vertical alinement with the center of the canister, a plunger disk mounted within said dash-pot, a cushion spring resiliently supporting said disk, and means 35 whereby the handle of a mop may be supported by said disk and reciprocated against the expansion of the spring in a manner to cause the mop to be violently shaken within the canister, and dust removed therefrom, 40 and a removable lining adapted to be positioned within the canister to receive the dust and lint from the mop.

In testimony whereof we have signed our names to this specification.

ALICE W. HARRISON.
HELEN WARD BASCOM.
